[57] ABSTRACT

A floating burner apparatus for accommodating combustion of gas coming from a submarine petroleum installation. A flue is provided for the combustion of the gas, which flue is supported at a buoy having a positive floatability in such a manner that the upper end of the flue is maintained above the level of the body of water during predetermined surface wave or billow conditions of the body of water, as well as during predetermined expected water current forces acting on the apparatus. In each of the embodiments, a principle flexible fluidtight conduit serves for simultaneously anchoring the buoy and for transferring gas from the submarine petroleum installation. In certain preferred embodiments, the buoy is immersed under the surface of the water so as to limit the effects of the billow thereon. Also, certain preferred embodiments include two buoys, one at the surface, and one submerged. Pilot or night lighting systems are provided which include a night light gas reservoir formed in one of the buoys. Several preferred embodiments include additional annular shaped stabilizing elements attached to the submerged buoys.

FLOATING BURNER APPARATUS FOR SUBMARINE PETROLEUM INSTALLATIONS

BACKGROUND AND SUMMARY OF THE INVENTION

The present invention relates to a floating burner (lamp or torch) which permits carrying out the combustion of gas from a submarine petroleum installation.

The operation of submarine petroleum fields requires immersion of the petroleum installations at greater or lesser depths. As is well known to the experts in operation of such submarine petroleum fields, the use of emerging platforms being supported on the bottom of the body of water for supporting the burners or torches generally associated with these immersed petroleum installations has drawbacks, such as high costs, difficulties of anchoring, maintenance, control, and so forth, since these platforms must withstand all the actions or activities produced by the meteorological and marine conditions of the spot where they are implanted.

It is therefore proposed by the present invention to provide floating burners or torches for immersed petroleum installations, which floating burners or torches render it possible to eliminate the drawbacks mentioned hereinabove.

In the below-described preferred embodiments of the invention, advantageous features with regard to night or pilot lighting systems and with regard to optimizing stabilization of the flue for the combustion of gases, are disclosed. The advantages of each of these preferred embodiments will be self-evident to one skilled in the art given the disclosure herein.

BRIEF DESCRIPTION OF THE DRAWINGS

FIG. 1 is a side schematic view of a first embodiment of the present invention;

FIG. 2 is a side view of a second embodiment of the present invention;

FIG. 3 is a side schematic view of a third embodiment of the present invention;

FIG. 4 is a side schematic view of further embodiment of the present invention;

FIG. 5 is an enlarged perspective view of a portion of FIG. 4 which shows the immersed buoy equipped with a stabilizer element; and

FIGS. 6 to 9 represent in perspective various embodiments of the annular stabilizing element.

DETAILED DESCRIPTION OF THE DRAWINGS

Throughout the various views, like reference numerals are used to depict like structures.

In FIG. 1, the lamp or torch comprises a flue or flame passage 1 consisting, for example, of a tube from special steel. This flue is equipped with a static flame-stopping or flame-checking device 9 and is secured on the emerging portion of a floating buoy 2. The attachment of the flue 1 on the buoy comprises, for example, a shrouding (guy or stay) for the reinforcement of the flue 1 against bending or flection stresses.

The length of the flue 1 is chosen in such a manner that the upper end thereof which is positioned at a distance L from the level of the water 3 will not be covered by the waves irrespective of the positioning assumed by the buoy 2 during usage thereof.

The lamp or torch comprises moreover a flexible conduit 4 which is water-tight and gas-tight and whose essential functions are:

to assure the anchoring of the floating buoy 2 and to direct or forward the gas that must be burnt between the immersed petroleum installation and the torch flue.

The flexible conduit 4 being utilized preferably has, for example but in a non-limitative manner, at least some and preferably all of the following characteristic elements or features:

an armature for withstanding the pressure differences prevailing inside and outside the conduit, consisting of at least one sheet or stratum formed by a helical winding, at short pitch, of a metallic profile having, for example, an S-shaped or Z-shaped cross section allowing for the clamping of adjacent turns; an armature for withstanding the traction and/or flection stresses, composed for example of two sheets or strata of wires, strands, or metallic profiles, being wound helically and in inverse directions along or following an important winding pitch, and at least one flexible water-tight casing or armoring for assuring the internal seal or tightness of the flexible conduit and, also the seal or tightness of the flexible conduit with respect to the outside medium, this casing or armoring consisting of a material such as a plastomer or an elastomer having a good behavior or holding power relative to the gases circulating in the conduit.

The lower end of the flexible conduit 4 is attached by any known means to an anchoring mass 5 resting on the bottom of the ocean, and this mass 5 may be a constituent element of the immersed petroleum installation (not shown) without departing from the spirit and scope of the present invention.

The device for fixing or securing the lower end of the conduit 4 allows for having the interior of conduit 4 communicate with a duct or line 6 placed on the bottom of the body of water and in which the gas flows that comes from the petroleum installation that must be burnt in the lamp or torch.

A lower hawsehole 7 which is integral with the anchoring mass 5 surrounds the lower end of the flexible conduit 4. This lower hawsehole 7, which has an internal surface that widens upwardly, avoids or prevents any excessive deformation of the lower end of the conduit 4 when the latter is subjected to a significant flection or bending stress.

The upper end of the flexible conduit 4 is secured by any known means to the floating buoy 2, and this securing device or means causes the flexible conduit to communicate with the lower end of the flue 1. An upper hawsehole 8 which is integral with the buoy 2 surrounds the upper end of the flexible conduit 4. This upper hawsehole 8, whose inner surface widens downwardly limits the deformations of the upper end of the conduit 4 when the latter is subjected to significant flection stresses.

The lower and upper hawseholes 7 and 8 may be integral with the ends of the flexible conduit 4 or with the devices for securing these ends in accordance with preferred embodiments of the invention.

As is apparent from FIG. 1, the length of the flexible conduit is at least equal to the depth H of the section of water in which the lamp or torch is placed.

In the embodiment shown in FIG. 1, the form or shape is chosen for the buoy 2 that yields or produces the smallest or weakest dynamic anchoring reactions, and, as shown, this shape is preferably the form of a caulked disk (frustrums of cones connected at their

bases). Moreover, the buoy 2 is given a positive floatability, i.e. a floatability of a value greater than the sum of the weight of the flue, of the buoy, and of the apparent weight of the flexible conduit in the water, in such a manner that the torque forces tending to invert the buoy due to the action of wind or a marine current remains very much lower than the buoyancy torques for straightening the buoy.

FIG. 2 schematically illustrates another embodiment of a floating lamp or torch as proposed by the present invention, equipped with night lights and lighting means. In this embodiment, the flue 1 whose upper end is located at the distance L above the level of the water 3 is secured on a hollow buoy 2a having a positive floatability and which is immersed at a depth P sufficient for avoiding or limiting the actions or force effects of the billow (surface waves), while still allowing for the intervention of divers. This buoy 2a is connected to the anchoring mass 5 resting on the bottom of the body of water by the flexible conduit 4 in the manner described above with respect to FIG. 1. The buoy 2a is preferably given a spherical shape which offers or affords an essentially identical hold in all directions with respect to the marine currents (isotropy).

As in the embodiment of FIG. 1, the flexible conduit 4 communicates directly with the flue 1 for the flow of the gas which must be burnt. A second flexible conduit 4a is provided for connecting the duct or line 6 for the supply of gas to the interior volume of the buoy 2a. In this manner the buoy 2a may be used as gas reservoir.

In FIG. 2, the duct or line 4a has been disposed coaxially to the interior of the conduit 4.

A duct or line which has been schematically shown at 10 and whose one end is in communication with the interior of the buoy 2a while the other end thereof is positioned in the vicinity of the upper end of the flue 1, serves for supplying a night light (low burner, pilot light).

A lighting device or means schematically shown at 11 is carried by the immersed buoy 2a. This device 11 which may be of any known type will not be described herein in detail. It is noted only that device 11 may preferably be of the type producing electric impulses producing sparks at the level of the night lights.

FIG. 3 schematically depicts a third embodiment according to the present invention in which the flue 1 is attached to or secured on a floating buoy 2 connected by a flexible conduit 4' to a hollow immersed buoy 2a, which buoy 2a is connected to the anchoring mass 5 resting on the bottom of the water by the flexible conduit 4.

As in the case of the embodiment illustrated in FIG. 2, the buoy 2a serves as reservoir for storing the gas supplying the night lights 10. A flexible conduit 4a may be placed at the interior of the conduit 4 for separately supplying the buoy 2a with gas from the immersed petroleum installation.

The conduit 4 communicates directly with the flexible conduit 4' which itself is connected to the flue 1. Placed preferably at the interior of the conduit 4', a conduit 4a' connects the interior of the buoy 2a to the ducts or lines of the night lights 10. The lighting and control device or means 11 which is preferably of the type producing electric impulses is preferably secured on the immersed buoy 2a. A conductor 12 placed at the interior of one of the conduits 4' or 4a' transmits to the night light the electric impulses furnished by the device 11.

In the embodiment illustrated in FIG. 1, the lighting of the lamp or torch may be effected by a fuse. But it is also contemplated to provide on the floating buoy night lights and lighting means such as those described in FIGS. 2 and 3 by using the floating buoy 2 as reservoir for the gas supplying the night light circuits and by giving to the flue a length sufficient in order that the temperature resulting from the combustion not be too high at the level of the buoy so as to make it possible for the intervention of a workman for actuating the lighting circuits.

In the embodiments illustrated in FIGS. 2 and 3, the handling or manipulation of the device 11 or any other operation is to be effected by a diver. Devices such as non-return flap valves, not shown in FIGS. 2 and 3, are provided on the buoy serving as reservoir for storing the gas supplying the night lights.

FIG. 4 illustrates a modified embodiment relative to that illustrated in FIG. 2, in which, however, the night lights and lighting device has not been represented for the sake of greater clarity of illustration.

Despite the immersion of the buoy 2a, the floating burner is subjected to the effect of the billow, of the marine currents, and of the winds, which impose upon the floating burner vertical movements, or pounding or ramming movements, and/or rolling and pitching movements. In order to minimize these movements and so as to obtain a great degree of stability, the floating burner according to the preferred embodiment of the present invention illustrated in FIG. 4 comprises a stabilizing element 12 supported by the buoy 2a and disposed at a certain distance under the latter to which it is connected, for example by arms such as the three arms 13, 14 and 15.

This stabilizing element 12 which constitutes an equalizing means has an annular shape and forms a skirt surrounding the flexible conduit 4 (see FIG. 5). The stabilizing element 12 will have as reduced as possible a transverse or horizontal cross section so as to minimize the action or effect of the vertical component of the billow on this stabilizing element.

By virtue of the existence of this stabilizing element 12, it is possible to reduce the horizontal cross section 45 of the buoy 2a, and, consequently, to minimize the action of the vertical component of the billow thereon since this cross section decrease may be compensated for by an increase in the height of the buoy 2a so as to preserve for this buoy the same volume, which is to say, 50 the same floatability, without jeopardizing the stability of the floating burner.

In fact, the increase in height of the buoy 2a results in an increased influence of the horizontal forces tending to include the burner, but the action of these forces is 55 counterbalanced by the opposing action or effect of the horizontal forces being exerted on the lateral surface of the stabilizing element 12 since this element 12 and the buoy 2a are positioned on both sides of the horizontal rocking axis of the burner.

60 The stabilizing element 12 is preferably constituted by at least one skirt as shown in FIGS. 4 and 5. In other preferred embodiments, the stabilizing element is formed with other rotating surfaces (surfaces of revolution), for example in the form of truncated cones 12' (FIG. 6). The stabilizing element 12'' of FIG. 7 consists of at least one essentially annular skirt whose cross section is not a surface of revolution but has, a polygonal shape, particularly a square shape.

The stabilizing element of FIG. 8a consists of two coaxial skirts 12, 12b connected by elements such as the crosspieces 16 so as to offer a minimum of hold or resistance to the vertical component of the billow. In the stabilizing element of FIG. 8b plates 17, with orifices, connect skirts 12a, 12b and also offer minimum resistance to the vertical component of the billow. The stabilizing element of FIG. 9 includes at least two coaxial skirts 12a', 12b' which allows for an optimum regulation or design control of the ratio e/h of the wall thickness of the stabilizing element to its height.

The positive floatability of the buoy 2a is chosen to be sufficient for keeping the flexible conduit 4 constantly under tension (this tension being compatible with the resistance of this conduit) despite the action of the billow periodically applying to the structure descending vertical forces.

This keeping of the flexible conduit 4 under tension decreases the risks of a rupture of the latter under the effect of the alternating vertical forces due to the billow. For the same purpose the length of the conduit 4 is chosen in such a manner that the buoy 2a remains immersed even for the maximum hollow of the waves.

The inner radius of the annular stabilizing element 12 (12a, 12b, 12a', 12b') is chosen to be greater than the maximum spacing or distance between the flexible conduit 4 and the axis of this element at the level of the latter, corresponding to the maximal inclination of the burner on the horizontal under the action or effect of the currents as well as of the winds acting upon the emerging portion of the flue 1 so that the annular element 12 cannot come to be supported on the flexible conduit 4 in the course of this inclination, which would eliminate any possibility of a restrengthening of the burner.

Further modifications are contemplated by the present invention which may be applied to the above described preferred embodiments without departing from the spirit and scope of the present invention. For example, in the embodiment of FIG. 3 the conduits 4' and 4 may constitute a single conduit, the buoy 2a being integral with this conduit which either extends through it or passes by in the immediate vicinity thereof.

It is also contemplated by the present invention to equip the buoy 2 (FIG. 1) or one and/or the other of the buoys 2 and 2a (FIG. 3) with a stabilizing element 12.

While we have shown and described several embodiments in accordance with the present invention, it is understood that the same is not limited thereto but also contemplates numerous changes and modifications as would be known to those skilled in the art given the present disclosure of the invention, and we therefore do not wish to be limited to the details shown and described herein only schematically but intend to cover all such changes and modifications.

We claim:

1. Floating burner apparatus for accommodating combustion of gas coming from a submarine petroleum installation, said apparatus comprising:
  - a flue for the combustion of said gas,
  - a buoy having a positive floatability, said flue being secured to said buoy with the upper end of said flue maintained above the level of a body of water within which said buoy is floated, and
  - a principal fluid tight conduit serving simultaneously for anchoring said buoy and for transferring gas from the submarine petroleum installation to said

flue, one end of said principal conduit being secured to said buoy and communicating with said flue, the other end of said principal conduit being connected to anchoring apparatus at the bottom of the body of water and communicating with the submarine petroleum installation,

wherein said principal conduit has a length at least equal to the distance separating the bottom and the surface of the body of water in such a manner that said buoy floats on the water surface, and wherein said conduit is flexible so as to accommodate movement of said buoy in response to a drop in the level of the body of water within which said buoy is floated.

2. Apparatus according to claim 1, wherein the principal conduit is armored.

3. Floating burner apparatus for accommodating combustion of gas coming from a submarine petroleum installation, said apparatus comprising:

a flue for the combustion of said gas,
a buoy having a positive floatability, said flue being secured to said buoy with the upper end of said flue maintained above the level of a body of water within which said buoy is floated, and
a principal flexible fluid tight conduit serving simultaneously for anchoring said buoy and for transferring gas from the submarine petroleum installation to said flue, one end of said principal conduit being secured to said buoy and communicating with said flue, the other end of said principal conduit being connected to anchoring apparatus at the bottom of the body of water and communicating with the submarine petroleum installation,

wherein said principal conduit has a length at least equal to the distance separating the bottom and the surface of the body of water in such a manner that said buoy floats on the water surface, and wherein said apparatus further comprises a second buoy having a positive floatability which is immersed and is integrally connected with said principal flexible conduit.

4. Floating burner apparatus for accommodating combustion of gas coming from a submarine petroleum installation, said apparatus comprising:

a flue for the combustion of said gas,
a buoy having a positive floatability, said flue being secured to said buoy with the upper end of said flue maintained above the level of a body of water within which said buoy is floated, and
a principal flexible fluid tight conduit serving simultaneously for anchoring said buoy and for transferring gas from the submarine petroleum installation to said flue, one end of said principal conduit being secured to said buoy and communicating with said flue, the other end of said principal conduit being connected to anchoring apparatus at the bottom of the body of water and communicating with the submarine petroleum installation,

wherein said principal conduit has a length at least equal to the distance separating the bottom and the surface of the body of water in such a manner that said buoy floats on the water surface,

wherein said apparatus further comprises a system of night lights, lighting, and control means, wherein said system is supported by said buoy and wherein said buoy is hollow and constitutes a reservoir for storing gas for supplying the system of night lights.

5. Floating burner apparatus for accommodating combustion of gas coming from a submarine petroleum installation, aid apparatus comprising:

a flue for the combustion of said gas,
a buoy having a positive floatability, said flue being secured to said buoy with the upper end of said flue maintained above the level of a body of water within which said buoy is floated, and
a principal flexible fluid tight conduit serving simultaneously for anchoring said buoy and for transferring gas from the submarine petroleum installation to said flue, one end of said principal conduit being secured to said buoy and communicating with said flue, the other end of said principal conduit being connected to anchoring apparatus at the bottom of the body of water and communicating with the submarine petroleum installation,
wherein said principal conduit has a length smaller than the distance separating the bottom and the surface of the body of water in such a manner that said buoy is immersed at a depth sufficient for protecting said buoy at least partially from the action of the billow,

wherein said apparatus further comprises a system of 25 night lights, lighting, and control means, wherein said system is supported by said buoy and wherein said buoy is hollow and constitutes a reservoir for storing gas for supplying the system of night lights.

6. Apparatus according to claim 3, further comprising a system of night lights, lighting, and control means, wherein said second buoy is hollow and constitutes a reservoir for storing gas for supplying the system of night lights.

7. Appatatus according to claim 4, wherein the gas supplying said system of night lights comes from the submarine petroleum installation and is stored intermediately in the buoy forming said reservoir and which is equipped for this purpose with means for the supply with gas coming from the petroleum installation.

8. Apparatus according to claim 5, wherein the gas supplying said system of night lights comes from the submarine petroleum installation and is stored intermediately in the buoy forming said reservoir and which is equipped for the purpose with means for the supply with gas coming from the petroleum installation.

9. Apparatus according to claim 6, wherein gas supplying said system of night lights comes from the submarine petroleum installation is stored intermediately in the buoy forming said reservoir and which is equipped for this purpose with means for the supply with gas coming from the petroleum installation.

10. Apparatus according to claim 7, wherein said means for supplying the reservoir-buoy with gas consist of an auxiliary fluid-tight flexible conduit which directly connects said reservoir-buoy with the submarine petroleum installation.

11. Apparatus according to claim 8, wherein said means for supplying the reservoir-buoy with gas consist of an auxiliary fluid-tight flexible conduit which directly connects said reservoir-buoy with the submarine petroleum installation.

12. Apparatus according to claim 9, wherein said means for supplying the reservoir-buoy with gas consist of an auxiliary fluid-tight flexible conduit which directly connects said reservoir-buoy with the submarine petroleum installation.

13. Apparatus according to claim 7, wherein said auxiliary conduit is placed at the interior of said principal conduit.

14. Apparatus according to claim 11, wherein said auxiliary conduit is placed at the interior of said principal conduit.

15. Apparatus according to claim 12, wherein said auxiliary conduit is placed at the interior of said principal conduit.

16. Apparatus according to claim 3, further comprising a stabilizing element constituting an equalizing means which is disposed under and supported by said second buoy, wherein said stabilizing element is essentially annular in shape and surrounds said principal conduit.

17. Floating burner apparatus for accommodating combustion of gas coming from a submarine petroleum installation, said apparatus comprising:

a flue for the combustion of said gas,
a buoy having a positive floatability, said flue being secured to said buoy with the upper end of said flue maintained above the level of a body of water within which said buoy is floated, and
a principal flexible fluid tight conduit serving simultaneously for anchoring said buoy and for transferring gas from the submarine petroleum installation to said flue, one end of said principal conduit being secured to said buoy and communicating with said flue, the other end of said principal conduit being connected to anchoring apparatus at the bottom of the body of water and communicating with the submarine petroleum installation,

wherein said principal conduit has a length at least equal to the distance separating the bottom and the surface of the body of water in such a manner that said buoy floats on the water surface,

wherein said apparatus further comprises a stabilizing element constituting an equalizing means which is disposed under and supported by said buoy, and wherein said stabilizing element is essentially annular in shape and surrounds said principal conduit.

18. Floating burner apparatus for accommodating combustion of gas coming from a submarine petroleum installation, said apparatus comprising:

a flue for the combustion of said gas,
a buoy having a positive floatability, said flue being secured to said buoy with the upper end of said flue maintained above the level of a body of water within which said buoy is floated, and
a principal flexible fluid tight conduit serving simultaneously for anchoring said buoy and for transferring gas from the submarine petroleum installation to said flue, one end of said principal conduit being secured to said buoy and communicating with said flue, the other end of said principal conduit being connected to anchoring apparatus at the bottom of the body of water and communicating with the submarine petroleum installation,

wherein said principal conduit has a length smaller than the distance separating the bottom and the surface of the body of water in such a manner that said buoy is immersed at a depth sufficient for protecting said buoy at least partially from the action of the billow,

wherein said apparatus further comprises a stabilizing element constituting an equalizing means which is disposed under and supported by said buoy, and

wherein said stabilizing element is essentially annular in shape and surrounds said principal conduit.

19. Apparatus according to claim 17, wherein the distance between the axis of said essentially annular stabilizing element and the inner wall of this stabilizing element is greater than the maximum distance and spacing of the principal conduit and the axis of the stabilizing element at the level of the latter under the effect of the horizontal components of the forces being exerted on the floating burner apparatus.

20. Apparatus according to claim 18, wherein the distance between the axis of said essentially annular stabilizing element and the inner wall of this stabilizing element is greater than the maximum distance and spacing of the principal conduit and the axis of the stabilizing element at the level of the latter under the effect of the horizontal components of the forces being exerted on the floating burner apparatus.

21. Apparatus according to claim 16, wherein the distance between the axis of said essentially annular stabilizing element and the inner wall of this stabilizing element is greater than the maximum distance and spacing of the principal conduit and the axis of the stabilizing element at the level of the latter under the effect of the horizontal components of the forces being exerted on the floating burner apparatus.

22. Apparatus according to claim 19, wherein said stabilizing element comprises at least one skirt having a surface of revolution.

23. Apparatus according to claim 21, wherein said stabilizing element comprises at least one skirt having a surface of revolution.

24. Apparatus according to claim 22, wherein said stabilizing element has an essentially cylindrical wall.

25. Apparatus according to claim 23, wherein said stabilizing element has an essentially cylindrical wall.

26. Apparatus according to claim 22, wherein said stabilizing element has at least one truncated-conical wall.

27. Apparatus according to claim 23, wherein said stabilizing element has at least one truncated-conical wall.

28. Apparatus according to claim 19, wherein said stabilizing element comprises at least one skirt whose cross section has a polygonal shape.

29. Apparatus according to claim 21, wherein said stabilizing element comprises at least one skirt whose cross section has a polygonal shape.

30. Apparatus according to claim 19, wherein said stabilizing element comprises at least two coaxial skirts.

31. Apparatus according to claim 21, wherein said stabilizing element comprises at least two coaxial skirts.

32. Apparatus according to claim 30, wherein said coaxial skirts are concentric and rigidly connected to one another by junction elements offering a minimum of resistance to the vertical component of the forces of the billow of said body of water.

33. Apparatus according to claim 31, wherein said coaxial skirts are concentric and rigidly connected to one another by junction elements offering a minimum of resistance to the vertical component of the forces of the billow of said body of water.

34. Apparatus according to claim 17, wherein said coaxial skirts constitute a telescopic assembly.
